UNITED STATES PATENT OFFICE.

CHARLES M. GENTHNER, OF MIDDLETOWN, PENNSYLVANIA, ASSIGNOR TO WINCROFT STOVE WORKS, OF MIDDLETOWN, PENNSYLVANIA, A CORPORATION OF PENNSYLVANIA.

DESIGN FOR A COOKING-STOVE.

42,795.

Specification for Design.

Patented July 16, 1912.

Application filed May 10, 1912. Serial No. 696,508. Term of patent 7 years.

To all whom it may concern:

Be it known that I, CHARLES M. GENTHNER, a citizen of the United States, and a resident of Middletown, in the county of Dauphin and State of Pennsylvania, have invented a certain new, original, and ornamental Design for a Cooking-Stove, of which the following is a specification, reference being had to the accompanying drawing, forming part thereof.

The figure is a perspective view of a cooking stove, showing my new design.

I claim:

The ornamental design for a cooking stove, as shown.

In testimony whereof, I affix my signature, in the presence of two witnesses.

CHARLES M. GENTHNER.

Witnesses:

CHARLES S. PRIZER,
DAVIS L. GARVER.
